DISPENSING FAUCET

Filed May 18, 1942

UNITED STATES PATENT OFFICE

2,367,077

DISPENSING FAUCET

Lawrence T. Ward, Philadelphia, Pa., assignor to
 Knapp-Monarch Company, St. Louis, Mo., a
 corporation of Missouri

Application May 18, 1942, Serial No. 443,453

12 Claims. (Cl. 222—18)

My present invention has to do with a dispensing faucet which employs compressed gas bulbs for supplying the dispensing pressure, the gas therefrom being under control of the faucet in addition to the handle of the faucet being operable to control liquid flow from the faucet.

One object of the invention is to provide a dispensing faucet having an operating handle formed by a compressed gas bulb holder, the liquid valve of the faucet being openable as desired, and upon the final opening movement effecting the opening of a gas valve for admitting gas from the compressed gas bulb in the faucet handle to the liquid container for displacing the liquid therefrom.

Another object is to provide a faucet designed to be used in conjunction with a container of liquid or beverage which has a delayed pressure action, that is, the liquid valve opens first, allowing the liquid or beverage to be drawn off until the pressure within the container is reduced, further opening of the dispensing faucet then causing the gas valve to be opened to admit additional gas to replenish the reduced pressure.

Another object is to provide a dispensing faucet wherein a single movement of the faucet handle controls the withdrawal of liquid and the introduction of dispensing pressure.

Still another object is to provide a dispensing faucet wherein a tapered stem or other type of rotary valve may be rotated by manipulating the handle thereof, a screw-threaded or needle type of valve being associated with the liquid dispensing valve for controlling the flow of compressed gas into the liquid or beverage container.

Still a further object is to provide a gas valve designed to remain inoperable until the faucet handle has been moved most of the way from closed position to full open position of the liquid valve, further movement of the handle thereupon causing the gas valve to be opened for admitting gas under pressure into the container, as desired.

With these and other objects in view, my invention consists in the construction, arrangement and combination of the various parts of my device whereby the objects contemplated are attained, as hereinafter more fully set forth, pointed out in my claims and illustrated in the accompanying drawing. Although the invention is susceptible of a variety of embodiments, it is unnecessary to fully describe and illustrate more than one in order to give a full understanding of the invention both from its structural and functional standpoints. Accordingly, I have illustrated a pre-

ferred and desirable embodiment of the invention in the accompanying drawing, in which:

Figure 1 is a vertical sectional view through a dispensing faucet embodying my invention;

5 Figure 2 is an enlarged sectional view on the line 2—2 thereof, showing the liquid valve of the faucet in closed position;

Figure 3 is a similar sectional view showing the liquid valve in partially opened position;

10 Figure 4 is a similar sectional view showing the liquid valve moved past wide open position;

Figure 2a is a sectional view on the line 2a—2a of Figure 1, showing certain parts of the gas valve of the dispensing faucet in the position assumed 15 corresponding to the liquid valve in its Figure 2 position;

Figures 3a and 4a are similar sectional views showing the gas valve mechanism of Figure 2 in the positions assumed thereby corresponding to 20 the Figure 3 and Figure 4 positions respectively of the liquid valve; and

Figure 5 is an enlarged sectional view similar to a portion of Figure 1, showing the gas valve in open position.

25 On the accompanying drawing I have used the reference character B to indicate generally a valve body, and H the handle of the faucet. The valve body B has a spout 10 in which a liquid discharge passageway 12 is formed. The passageway 12 communicates with a syphon tube 13, depending from the valve body B into a container C, such as a barrel or keg, the bottom of which is indicated at 14 and the top thereof indicated at 15.

The valve B has a threaded portion 16 on which 30 a union nut is threaded. The nut 17 rotates on a nipple 18 threaded into a bushing 19 in the container head 15. A suitable gasket 19a is provided for sealing the union joint. The parts 16, 17 and 19 permit ready detachability of the valve body B with respect to the container C for changing 35 from one empty container to a full one.

The valve body B has a tapered bore 20 in which is rotatably mounted a tapered valve stem 21. The valve stem 21 is retained tight in the bore 20 by a pressure spring 22 backed by a retainer nut 23. The spring 22 is interposed between the head of the nut 23 and a flange 24 surrounding the valve stem 21. The valve stem 21 constitutes a liquid valve which has a passageway 25 therethrough to register with the liquid discharge passageway 12 when liquid is to be dispensed. A boss 21a passes through the passageway 25 to carry a passageway 35 across it.

The handle H includes a fitting 26 securely 40 threaded on the upper end of the valve stem 21

and a holder 27 for a gas bulb 28. The neck of the gas bulb 28 is adapted to be sealed in a rubber sleeve 29 when the holder 27 is screwed onto the fitting 26, and to be pierced by a piercing pin 30. The pin 30 is part of a fitting 31, and the two are hollow or provided with a bore, shown by dotted lines 32.

The fitting 26 has therein an insert 33 of carborundum or ceramic material to permit only slow flow of gas therethrough. The gas that passes through the insert then enters a passageway 34 in the valve body 26. The liquid valve stem 21 has the gas passageway 35 extending vertically therethrough and communicating at its upper end with the passageway 34. At the lower end of the passageway 35 a pressure valve seat 36 is provided.

A gas valve plug 37 is screwed into the lower end of the valve stem 21 for coaction with the seat 36. The valve plug 37 has a serrated portion 38 on which is slidably and non-rotatably mounted a sleeve 39. The sleeve 39 is serrated to fit the gas valve plug 37. The purpose of the serrations 38 in the gas valve plug 37 is to permit adjustment of the sleeve 39 when the faucet is assembled and to take care of wear, if any, on the gas valve seat 36 after the faucet has been in use for some time.

The sleeve 39 has a stop lug 40 projecting therefrom. A coil spring 41 has ends 42 and 43 hooked over the stop lug 40 and extending into a socket 44 of the valve stem 21, with the spring under tension to normally rotate the valve plug 37 to seated position with respect to the seat 36. The valve plug 37 has a head or nut 45 on its lower end to retain the sleeve 39 in position.

The sleeve 39 and the nut 45 are rotatable in a bore 46 of the valve body B, whereas the stop lug 40 swings in an enlarged portion 47 of the bore 46. The enlarged portion 47 terminates at its ends in stop shoulders 48 and 49. To show a maximum of detail in Figure 1, the sleeve 39 is shown about 90 degrees from its true position with relation to the stem 21.

Practical operation

In the operation of my valve, the handle H is normally left in the closed position indicated as H¹ in Figure 2. The sleeve 39 and its stop lug 40 and the hooked ends 42 and 43 of the gas valve spring 41 at that time assume the position shown in Figure 2a. The same position of these parts is shown in Figure 1, whereas the handle H and the valve stem passageway 25 are shown in open position to facilitate disclosure of the details thereof.

When it is desirable to dispense liquid, if there is pressure in the container C, it is merely necessary to move the handle H to, or nearly to, the position indicated at H² in Figure 3. It will be noted that the passageway 25 now communicates with the passageway 12 so that liquid can flow through the valve and out of the spout 10. The valve plug 37 is still closed against the valve seat 36 as the valve plug and the spring 41 have moved as a unit with the valve stem 21 to the position shown in Figure 3a.

If the pressure in the container C decreases to such an extent that it will no longer displace liquid through the spout 10, or if there was not enough pressure in the container C to cause such dispensation, then the handle H can be moved further, as to the position H³ in Figure 4, which will cause an opening of the valve plug 37. Such

opening occurs, due to the valve plug now being retained against rotation by the stop lug 40 having engaged the stop shoulder 48 and thereby prevented from further rotation. The valve stem 21, however, is rotated further, as evidenced by the position of the passageway 25 in Figure 4, and the end 43 of the spring 41 in Figure 4a. Since the valve plug 37 is threaded left-hand, this will cause unscrewing of the stem 21 with respect to the valve plug 37 and thereby a slight opening of the valve 36—37. This open position is shown in Figure 5.

Gas from the bulb 28 now passes through the piercing pin 30, the fitting 31, the insert 33, the passageway 34 and the passageway 35, thereupon flowing around the threads of the valve stem 37, which may be loose enough to permit such flow, and then enters a passageway 50 laterally from the bore 20, communicating with a vertical passageway 51 surrounding the syphon tube 13. The passageway 51 communicates with the interior of the container C adjacent the top thereof, so that the gas is thereby introduced on top of the liquid for displacing it through the syphon tube and the spout 10.

When the handle H is returned from the open position H³ to the closed position H¹, initial movement permits the valve plug 37 to be closed under action of the spring 41 by the time the position of Figures 3 and 3a is reached. Thereafter, the passageway 25, through the stem 21, is rotated to cut off communication with the passageway 12.

From the foregoing description it will be ob-

35 vious that I have provided a dispensing faucet which permits the liquid to be withdrawn at the same time the dispensing pressure is applied, or if dispensing pressure is present in the con-

40 tainer, then only the liquid valve need be opened. In the closing cycle, the gas valve shuts first, while the liquid passage is still open, so that in the event too much gas has been admitted to the container C, it may be partially dissipated by dispensing liquid from the spout 10 before

45 the liquid valve 21 is closed. A faucet of this character has a variety of applications. It can be used for dispensing most any type of liquid, such as water, beverage, chemicals, food con-

50 centrates and syrups, which are subject to oxidation. It can be used on containers of from one to fifty gallons or more capacity, as one of the bulbs 28 has a capacity for dispensing approximately a gallon of liquid. Therefore, by

55 using additional bulbs, the capacity of the faucet is increased to any extent desired. The faucet is particularly adapted to dispensing beer or carbonated beverages, because CO₂ gas is present in both, and the bulbs 28 are usually charged with CO₂ gas. A dispensing faucet of the type dis-

60 closed thereby supplants costly pressure systems now used for beer and fountain dispensation.

The bulbs 28, of course, need not be filled with CO₂ gas. If the liquid to be dispensed needs to be free from taste or chemical reaction, the contents of the bulbs could be of a different gas or air, or a combination of gases or air and gas.

Some changes may be made in the construction and arrangement of the parts of my device without departing from the real spirit and purpose of my invention, and it is my intention to cover by my claims any modified forms of structure, or use of mechanical equivalents, which may be reasonably included within their scope.

I claim as my invention:

1. In a dispensing faucet, a valve body having

a spout, a liquid discharge passageway through said body and spout, a siphon tube depending from said body for positioning in a container adjacent the bottom thereof, a liquid valve in said passageway, a handle for opening said liquid valve, a compressed gas bulb carried in said handle, said liquid valve having a gas passageway therethrough, communicating with said bulb and terminating in a valve seat, a gas valve comprising a valve plug for seating against said valve seat, spring means normally retaining said valve plug seated against said valve seat, means for unseating said valve plug from said valve seat as said handle is moved beyond a predetermined point at which said liquid valve is opened, and a passageway from the outlet side of said gas valve to the interior of the container adjacent the top thereof.

2. In a dispensing faucet, a valve body having a liquid discharge passageway therethrough, a siphon tube depending from said valve body for positioning in a container adjacent the bottom thereof, a liquid valve in said passageway, a handle for opening said liquid valve, said liquid valve having a gas passageway therethrough and terminating in a valve seat, a gas valve comprising a valve plug for seating against said valve seat, spring means normally retaining said valve plug seated against said valve seat, means for unseating said valve plug from said valve seat as said handle is moved beyond a predetermined point at which said liquid valve is opened, and a passageway from the outlet side of said gas valve to the interior of the container adjacent the top thereof.

3. In a dispensing faucet, a valve body having a bore, a perforated valve stem rotatable therein, a handle on said stem, said handle including a compressed bulb holder and a piercing pin for the bulb, said valve stem having a gas passageway therethrough and terminating in a valve seat, a gas valve plug threaded in said valve stem and having a lug projecting therefrom, a spring engaging said lug and said valve stem to rotate said gas valve plug to seated position with respect to said valve seat, a stop shoulder in said valve body for said lug to engage at a predetermined position in the rotation of said handle, whereby further rotation of the handle rotates said valve stem relative to said gas valve plug for thereby spacing the gas valve plug from said valve seat, a passageway from the outlet side of said gas valve to the interior of a container adjacent the top thereof, and a siphon tube depending from said valve body into the container adjacent the bottom thereof.

4. In a dispensing faucet, a valve body having liquid receiving and discharge passageways, a valve stem rotatable therein and having a lateral opening therethrough to connect said passageways with each other, said valve stem having a gas passageway axially therethrough and terminating in a valve seat, a gas valve plug threaded in said valve stem, means normally rotating said valve plug to seated position on said valve seat, stop means for said valve plug at a predetermined position in the rotation of said stem, a passageway from the outlet side of said gas valve to the interior of a container adjacent the top thereof, a siphon tube communicating at its upper end with said liquid receiving passageway depending from said valve body into the container adjacent the bottom thereof, and a union fitting for connecting said valve body with said container.

5. In a dispensing faucet, a valve body including a spout having a liquid discharge passageway therein, a siphon tube depending from said valve body and communicating with said passageway, said siphon tube being adapted for positioning in a container with its intake end adjacent the bottom thereof, a liquid valve in said passageway, a handle for opening said liquid valve by rotating movement thereof, a gas passageway in said liquid valve terminating in a gas valve seat, said liquid valve being threaded beyond said valve seat, a gas valve plug for seating against said valve seat and having a threaded stem coaxing with the threads of said liquid valve, said stem having a serrated portion, a sleeve thereon having a serrated bore receiving said serrated portion, said sleeve having a stop lug, a spring coiled around said sleeve and having ends hooked against said lug and into said liquid valve to normally rotate said stem to a position for closing said valve plug against said valve seat, said valve body having a stop shoulder engageable by said stop lug upon rotation of said liquid valve to a partially open position, further movement of said liquid valve to open position effecting relative movement of the threads of said liquid valve and gas valve plug whereby to space said valve plug from said valve seat to permit gas to flow therethrough, said valve body having a gas passageway from said valve seat into the container adjacent the top thereof.
6. In a dispensing faucet, a valve body including a spout having a liquid discharge passageway therein, a siphon tube depending from said valve body and communicating with said passageway, said siphon tube being adapted for positioning in a container with its intake end adjacent the bottom thereof, a liquid valve in said passageway, a gas passageway in said liquid valve terminating in a gas valve seat, said liquid valve being threaded beyond said valve seat, a gas valve plug for seating against said valve seat and having a threaded stem coaxing with the threads of said liquid valve, a sleeve slidable and non-rotatable on said stem, said sleeve having a stop lug, a spring coiled around said sleeve and having ends hooked against said sleeve and into said liquid valve to normally rotate said stem to a position for closing said valve plug against said valve seat, said valve body having a stop means engageable by said valve plug upon rotation of said liquid valve to a partially open position, further movement of said liquid valve to open position effecting relative movement of the threads of said liquid valve and gas valve plug whereby to space said valve plug from said valve seat to permit gas to flow therethrough, said valve body having a gas passageway from said valve seat into the container adjacent the top thereof.
7. In a dispensing faucet, a valve body including a spout having a liquid discharge passageway therein, a liquid valve in said passageway, a gas passageway in said liquid valve terminating in a gas valve seat, said liquid valve being threaded beyond said valve seat, a gas valve plug for seating against said valve seat and having a threaded stem coaxing with the threads of said liquid valve, said stem having a serrated portion, a sleeve thereon having a serrated bore receiving said serrated portion, a spring coiled around said sleeve and having ends hooked against the sleeve and into said liquid valve to normally rotate said stem to a position for closing said valve plug against said valve seat, said valve body having stop means for said stem when said liquid valve is

partially open whereby further movement of said liquid valve effects relative movement of the threads of said liquid valve and gas valve plug to space said valve plug from said valve seat.

8. In a dispensing faucet, a valve body including a spout having a liquid discharge passageway therein, a siphon tube depending from said valve body and communicating with said passageway, said siphon tube being adapted for positioning in a container with its intake and adjacent the bottom thereof, a liquid valve in said passageway opened by rotating movement thereof, a gas passageway in said liquid valve terminating in a gas valve seat, a gas valve plug for seating against said valve seat and being threaded into said liquid valve, a sleeve slidable and non-rotatable on said valve plug, said sleeve having a stop lug, a spring coiled around said sleeve and having ends hooked against said lug and into said liquid valve to normally rotate said valve plug to a position for closing said valve plug against said valve seat, said valve body having a stop shoulder engageable by said stop lug upon rotation of said liquid valve to a partially open position, further movement of said liquid valve to open position effecting relative movement of the threads of said liquid valve and gas valve plug whereby to space said valve plug from said valve seat to permit gas to flow therethrough, said valve body having a gas passageway from said valve seat into the container adjacent the top thereof.

9. In a dispensing faucet for a container of liquid, a valve body, a liquid valve therein, a handle for opening said liquid valve, a compressed gas bulb carried in said handle, said liquid valve having a gas passageway communicating with said bulb and terminating in a valve seat, said valve body having a passageway from said valve seat to the container, a gas valve comprising a valve plug screw threadedly carried by said liquid valve for seating against said valve seat, said plug, when unseated, permitting gas flow from the gas passageway of said liquid valve to the gas passageway of said valve body, spring means normally retaining said valve plug seated against said valve seat, and means in said valve body engaged by said valve plug to hold it against further movement with said handle as it is moved beyond a predetermined point to which said liquid valve is opened, said means thereupon effecting unscrewing and consequently unseating of said valve plug.

10. A dispensing faucet for a container of liquid comprising a valve body having a spout, a liquid discharge passageway through said body and spout, a liquid valve comprising a perforated stem across said passageway, a handle for rotat-

ing said stem, a compressed gas bulb, said stem having a gas passageway therethrough, communicating with said bulb and terminating in a valve seat, a gas valve comprising a valve plug threaded in said stem for seating against said valve seat, said plug, when open, establishing communication between said gas passageway of said stem and said gas passageway of said valve body, spring means normally rotating said valve plug relative to said stem to retain it seated against said valve seat, said valve plug engaging a portion of said body and being thereby stopped in rotation while permitting further rotation of said stem to thereby unseat the valve plug from said valve seat as said handle is moved beyond a predetermined point at which said liquid valve has been opened.

11. In a dispensing faucet for a container of liquid, a valve body having a tapered bore, a 20 tapered valve stem rotatable therein, said valve stem having a gas passageway therethrough and terminating in a valve seat at the inner end of the stem, said valve body having a gas passageway from said valve seat to the container, a gas 25 valve plug threaded in said inner end of said valve stem and having a lug projecting therefrom, a spring engaging said lug and said valve stem to rotate said gas valve plug to seated position with respect to said valve seat, a stop shoulder in said 30 valve body, said lug engaging thereagainst at a predetermined position in the rotation of said stem whereby further rotation of the stem rotates the threads of said valve stem relative to the threads of said gas valve plug and the valve 35 plug is spaced from said valve seat to thereby open communication between said gas passageway of said valve stem and said gas passageway of said valve body.

12. A dispensing faucet for a container of liquid comprising a valve body having a bore, a 40 valve stem rotatable therein having a gas passageway terminating in a valve seat, said valve body having a gas passageway from said valve seat to said container, a gas valve plug threaded 45 in said valve stem, means to normally rotate said valve plug to seated position with respect to said valve seat, said valve plug, when unseated, establishing communication between said gas passageway of said valve stem and said gas passageway of said valve body, and stop means for the rotation of said valve plug at a predetermined position in the rotation of said valve stem to thereby unthread the valve plug relative to the stem and effect spacing of said valve plug from said valve 50 seat upon further rotation of said valve stem.

LAWRENCE T. WARD.
